UNITED STATES PATENT OFFICE.

VICTOR LEE EMERSON, OF PHILADELPHIA, PENNSYLVANIA.

CLOSURE FOR BOILER-HEADERS.

1,352,254.

Specification of Letters Patent. Patented Sept. 7, 1920.

Original application filed May 8, 1919, Serial No. 295,541. Divided and this application filed November 3, 1919. Serial No. 335,562.

To all whom it may concern:

Be it known that I, VICTOR LEE EMERSON, residing at Philadelphia, in the county of Philadelphia and State of Pennsylvania, have invented certain new and useful Improvements in Closures for Boiler-Headers, of which the following is a specification.

To obtain a close fit of the closures on the clean-out holes of the headers in boilers it has generally been found that the hole must be made oval to permit the closing plate to be inserted and applied against the interior wall of the header. After insertion the plate must be partially rotated and clamped in close engagement with the inner wall by means of a yoke held against the outer wall and bolted to the plate. The clamping of the surface of engagement of the plate with the inner wall is difficult and uncertain. Due to the accumulation of dirt and scale it is a matter of considerable difficulty to establish a fluid-tight connection between the closure plate and the wall.

To adapt the header for double form of closure plate requires the machining of an oval hole and an oval form must be given to the closure plate.

My invention consists in the application of the closure plate to the outer surface of the wall and in a manner to insure a fluid-tight fit regardless of the condition of the opening.

It is also an object of my invention to simplify the manufacture of these clean-out holes by constructing a circular opening rather than one of irregular shape. The manufacture and machining of round parts is obviously quicker, cheaper and more satisfactory in point of use.

It is a further object of my invention to insure engagement between the closure plate, the retaining means and the co-operating adjustment means by the use of an improved bolt. By this means the parts will be self-aligning and self-centering, automatically establishing firm engagement.

A further object of my invention resides in providing through the above mentioned means a device which will close properly in the event that the plane of the wall of the header and the flange of the header are not in parallel planes.

My invention has for further object the advantages resultant from the use of an improved gasket which is self-positioning

and remains in position by reason of its special construction.

This application is a division of my application, Serial No. 295,541, filed May 8, 1919.

Other features will be apparent in my invention as set forth in the following description and drawings in which—

Figure 1 is a vertical section through a boiler header and

Fig. 2 is a vertical view of my improvement.

The boiler header noted generally in the drawings by the numeral 1 includes the rear wall 2. This wall is pierced to receive the tube 3 of the boiler. This tube is firmly fixed in the rear wall by means of welding or analogous agency 4. The rear wall may carry a large number of such tubes 3.

The front wall 5 of the header carries opposite each tube 3 a clean-out hole 6. This hole 6 is circular and conforms in size to the tube 3. The inner periphery of the hole 6 may be notched at diametrical points as at 7. The outer wall of the opening 6 carries a circular flange 8 having a curved surface 9. A gasket 10 of copper or other analogous material is adapted to contact with the curved surface 9 of the flange 8. The inner periphery of the gasket is struck up into a cylindrical flange member 11 which will slide snugly into the inner wall of the hole 6. In this manner the gasket may be placed upon the flange and will remain in position by reason of the member 11 contacting with the inner wall of the hole 6. The interior rim 11 moreover serves as additional means to prevent the escape of the fluid contained in the boiler.

A closure plate 12 is provided to fit over the opening 6. This closure plate has a plane surface 13. The plate is centrally recessed to provide a concave spherical surface for a purpose to be hereinafter described. Centrally of the plate is the circular opening 15.

Of smaller diameter than the opening 15 and extending therethrough, is the shank of the T-head bolt 16 with laterally extending extremities 17. These extremities 17 fit in the notches 7 of the wall 5 and serve to prevent the bolt 16 from rotation.

Due to the manner of casting such a header as is described above it will sometimes be found that the rear surface of the wall 5 will not be in a plane parallel to the

100

105

110

plane of the machined surface 9 on the flange 8.

- It follows that the bolt will rest with its axis perpendicular to the inner surface of the wall 5 and for this reason various points on the extremities 17 may rest against the notches 7. I therefore preferably form the surfaces of the extremities 17 convexed to insure uniform engagement in the notches 10 regardless of any displacement which may be caused in the bolt's position as a result of the flange 8 being inclined in its plane with respect to the plane of the rear surface of the wall.
- 15 The opposite end of the bolt 16 is screw-threaded as at 18 to receive a cap nut 19. This nut has a spherical bearing surface 20 which coöperates with the spherical surface 14 on the closure plate 12. In this manner 20 the nut 19 will serve to draw the plate 12 into position concentric with the bolt 16. At the same time the nut 19 will contact with the plate 12 on all sides irrespective of any inclination of the bolt from the position perpendicular to the plane surface 13.

25 The periphery of the nut 19 is flattened as at 21 to provide means for rotating the nut, for instance with a wrench. The outer portion of the nut 19 is given the form of 30 a cap 22 which prevents leakage of the fluid around the screw-thread of the bolt.

The manufacture of the above described parts is rendered simple since all operations are in a plane or in spherical surfaces. 35 The opening 6 being round contributes to ease of manufacture. In assembling the above structure the T-head bolt 16 is inserted through the round opening and its extremities 17 brought into loose engagement with the notches 7 on the interior wall. The gasket 10 is placed around the bolt 16 and brought into engagement with the curved surface 9 of the flange 8. The gasket centers itself without further treatment and 40 by virtue of the rim 11 remains fixed in position. The closure plate 12 may now be brought opposite the gasket and the nut 19 screwed upon the bolt. This brings the surface 20 in contact with the spherical 45 surface 14 of the closure plate and serves to move the latter in a lateral direction until the spherical surfaces are in coincidence with good bearing contact. The closure plate conforms to the plane of the flange surface 9 by the tilting movement 50 around the spherical surface 14. During this operation the bolt 16 and its extremities 17 have accommodated themselves in position against the notches 7 by reason 55 of the convexed surfaces of the extremities 17.

60 It will be manifest that during the closing operation there is no relative rotation between the flange 8, the gasket 10 and the plate 12. Thus the plate is pressed directly

against the gasket and compels a close fit. Since there is no rotary motion there is no tendency for the gasket to be stripped or forced out of position between the flange and plate.

70 The provision of the machined engagement surfaces on the outside rather than within the header makes refacing simple an economical. It can be accomplished by a cheap and simple tool, which in this type 75 of closure need not guard against injury to screw-threads generally found on closure holes adapted to be closed by plugs.

As above assembled the closure plate is constrained to take the proper position with 80 respect to the flange 8 and the axis of the bolt 16. The nut 19 insures a fluid-tight engagement between the closure plate and the boiler.

85 The particular embodiment of my invention is susceptible of considerable variation without departing from the spirit of my invention and it is to be understood that many changes may be made by those skilled in the art within the scope of the invention as defined in the appended claims.

90 What I claim as my invention is:

1. In a liquid vaporizer, a manifold comprising front and rear walls, the front walls having an externally flanged hand hole with 95 oppositely disposed recesses inclined to the plane of said flange on the internal rim, a cap, a T-head bolt seated in said recesses and passing through said cap and having an adjustable engagement with said recesses 100 and a nut on said bolt.

2. In a liquid vaporizer, a manifold comprising front and rear walls, the front wall having a hand hole, and recesses oppositely disposed with respect to said hole and inclined with respect to the plane of said front wall, a cap therefor having a central aperture and a spherical bearing surface, a nut with a corresponding spherical bearing surface and a T-head bolt in said hand hole 105 having an adjustable engagement with said recesses to hold the cap thereof.

3. A closure device for boiler hand holes comprising a T-headed bolt, having an adjustable engagement with the interior rim 115 of the hole, a cap having a machined inner surface adapted to coöperate with a machined up-turned circular flange around the exterior of the hole, said cap having a central aperture through which said bolt projects and free lateral movement with respect to said flange and a cap nut threaded on said bolt to force the cap into engagement with the flange.

4. In a liquid vaporizer, a header comprising front and rear walls, the front wall having a hand hole, a cap therefor having a universally movable engagement with said wall, means retaining the cap upon the external face of the wall and an internally 125 130

flanged gasket seated between the wall and cap.

5. In a liquid vaporizer, a header having a wall provided with a hand hole, said wall having an outwardly projecting flange surrounding said hand hole, and a closure device for said hand hole, said closure device and flange being so constructed as to have universally movable engagement with each 10 other.

6. In a liquid vaporizer, a header having a wall provided with a hand hole, said wall having recesses in the inner face thereof intersecting said hand hole at an angle to the outer surface of said wall, a closure member for said hand hole, and a retaining member for said closure member, said retaining member being so constructed as to be received in and adjustable in said recesses.

7. In a liquid vaporizer, a header having a wall provided with a hand hole, a flange on the outer face of said wall surrounding said hand hole and having a curved outer face, the inner face of said wall having recesses intersecting said hand hole, a closure member for said hand hole adapted to fit on the curved outer face of said flange, and a retaining member for said closure member so constructed as to be received in and adjustable in said recesses, said retaining member and closure member being so con-

structed as to have adjustable and universally movable connection therebetween.

8. In a liquid vaporizer, a header having a wall provided with a hand hole, a flange on the outer face of said wall surrounding said hand hole and having a curved outer face, the inner face of said wall having recesses intersecting said hand hole, a closure member for said hand hole adapted to fit on the curved outer face of said flange and having an aperture therein, a T-shaped retaining member for said closure member having freedom of movement in said aperture and its head so constructed as to be received in and adjustable in said recesses, and a nut on the outer end of said T-shaped retaining member, said nut and closure member being so constructed as to have universal adjustment relative to each other.

9. In a liquid vaporizer, a header having a wall provided with a hand hole, said wall having an outwardly projecting flange surrounding said hand hole and having a curved outer face, a closure member for said hand hole so constructed as to have universal adjustment with respect to said curved outer face of said flange, and a gasket between said closure device and said curved outer face of said flange.

In testimony whereof I have hereunto set my hand.

VICTOR LEE EMERSON.
